CARTON OR CONTAINER

Ralph Murray Glover, White Plains, N. Y., assignor, by mesne assignments, to Box Blank Corporation, New York, N. Y., a corporation of Delaware

Application October 2, 1941, Serial No. 413,256

15 Claims. (Cl. 229—9)

This invention relates to improvements in cartons or containers.

In general, a carton or container embodying the invention comprises a body part and a cover part, the body part being provided with an access or discharge opening preferably at one end and the cover part with a dispensing opening, preferably located at a lateral side, the body part and the cover part otherwise being devoid of opening, the aforesaid being combined with suitable means for effecting a restricted movement of the cover part relative to the body part to afford the dispensing of the contents, but maintaining at all times the cover part and the body part in relative telescopic engagement.

Embodiments of the invention are preferably formed of relatively stiff sheet material, such as paper stock, notably of cardboard, but may be formed of other sheet material having suitable characteristics for attaining the objects of the invention.

In general, the contents of the carton or container are dispensed through the dispensing opening of the cover part when the cover part has been moved to its maximum, i. e., restricted position in direction away from the major portion of the body part. The telescopic engagement-restricting and maintaining means may be arranged to afford a "snap" action in the movement of the cover part to its open and closed positions, respectively. The cover part may also be provided with stopper means whereby the access or discharge opening of the body part is sealed against leakage of flavor-imparting and/or aroma-imparting constituents of the material contained in the carton or container, also against "sifting" of contents, sealing against air, and the like.

Further features and objects of the invention will be more fully understood from the following detail description and the accompanying drawing, in which

Fig. 1 is a perspective view of one embodiment of the invention, illustrating the cover part and body part in closed position.

Fig. 2 is a similar perspective view of the embodiment shown in Fig. 1, and illustrating the cover part and body part in relative open position.

Fig. 3 is a longitudinal sectional view taken on line 3—3 of Fig. 1.

Fig. 4 is a longitudinal sectional view of Fig. 2.

Fig. 5 is a plan view of a blank suitable for forming the cover part of the embodiment of Figs. 1 through 4 of integral construction.

Fig. 6 is a plan view of a blank suitable for forming a body part of the embodiment of Figs. 1 through 4 of integral construction.

Fig. 7 is a perspective view of another embodiment of the invention illustrating the cover part and body part in relative open position.

Fig. 8 is an enlarged elevational detail view of the cover part and adjacent body part of Fig. 7 partly broken away in longitudinal section to illustrate otherwise hidden parts.

Fig. 9 is a similar view, broken away on a longitudinal section at right angles to that of the broken-away section of Fig. 8.

Fig. 10 is a detail sectional view taken on line 10—10 of Fig. 9.

Fig. 11 is a plan view of a blank suitable for forming the cover part of the embodiment of Figs. 7 through 10 of integral construction.

Fig. 12 is a plan view of a blank suitable for forming a body part of the embodiment of Figs. 7 through 10 of integral construction, an intermediate portion of the blank being broken away for reduction of showing.

Referring to the embodiment shown in Figs. 1 through 4, the same as shown comprises a body part 20 and cover part 21. The body part 20 is shown as provided with an access or discharge opening, indicated at 20a, see Figs. 3 and 4, disposed at its upper end as positioned in Figs. 1 through 4. The body part 20 otherwise is imperforate.

As illustrated, the body part is of rectangular cross-section, but may be of any desired polygonal or other cross-section. The bottom 20b of the body part 20 is closed; as illustrated, the bottom 20b is formed to be closed pursuant to conventional practice.

The cover part 21 is provided with a dispensing opening 21a which may be of any configuration and located as desired in accord with the invention. As illustrated in Figs. 1 through 4, the dispensing opening 21a is disposed on a lateral side of greater dimension of the cover part and closely adjacent the closed end 21b of the cover part.

The cover part 21 is associated with the body part 20 to restrict movement of the cover part in direction away from the major portion of the body part (to thereby dispense the contents as referred to more fully hereinafter) and to retain the cover part 21 at all times in telescopic engagement with the body part adjacent the portion thereof proximate the access opening 20a of the body part. Any suitable means for carrying out such function and relationship may be em-

ployed. As on suitable means for carrying out such function and relationship, as illustrated in Figs. 1 through 4, the restricting and retaining means comprising one or more extensions 22 of relatively stiff material one end of each such extension projecting from or otherwise is secured to the material of the sides of the body part 20 and adjacent its access opening 20a, the other end of each such extension being secured to the inner face of the top 21b of the cover part. In the embodiment illustrated, two such extensions 22, 22, are employed. To enhance the yieldability of such relatively stiff extensions 22, 22, the same may be weakened at portions thereof, such as the illustrated one or more score lines, indicated at 22a, preferably disposed proximately centrally and extending transversely of the longitudinal dimension of the extensions 22, 22.

It is noted that the dispensing opening 21a of the cover part 21 is disposed in the indicated lateral side of the cover part 21 to secure closure of the dispensing opening 21a and therewith of the access opening 20a of the body part 20 when the cover part 21 and the body part 20 are in maximum telescopic engagement, i. e., when the cover part has been moved to the limit toward the major portion of the body part. Upon relative movement of the cover part in direction away from the major portion of the body part 20 under restriction by the one or more extensions 22, the dispensing opening 21a is opened to greater and greater extent and is opened to maximum extent upon full movement of the cover part 21 in the stated direction.

Figs. 1 and 3 illustrate the closed position of the dispensing opening 21a and Figs. 2 and 4 the full open position of the dispensing opening 21a. Regulation of the effective area of opening of the dispensing opening 21a is attained by locating the same with relation to the marginal line indicated at 23a, i. e., the spacing of the proximate edge of the dispensing opening 21a from the marginal line 23a, see Fig. 5, indicating the intersection of the applicable lateral side of the cover part 21 and the closed end 21b of the cover part 21.

Embodiments of the invention typified by Figs. 1 through 4 may be charged by charging the to-be-dispensed contents through the opened bottom 20b of the body part; the bottom 20d is thereafter closed.

The blanks illustrated in Figs. 5 and 6 indicate suitable means for forming the cover part and the body part of the embodiment shown in Figs. 1 through 4 of integral construction. Panels of these blanks corresponding to the parts of the embodiment shown in Figs. 1 through 4 bear like reference characters. It will be observed also that the panels 23 respectively extending from the material of the two larger dimensioned and the two smaller dimensioned lateral sides of the cover part 21 serve to close the top 21b of the cover part. The panel 24 combines with the extreme right hand panel of the cover part 21 to afford overlapping "glue" areas for attaining the hollow configuration of the cover part. The panels of the blank shown in Fig. 6 indicate similarly the formation of the body part 20 of integral construction. Fig. 6 also shows the extensions 22 as formed integral with the material of panels forming two oppositely positioned lateral sides of the body part 20. The score lines 22b serve as hinges for the respective extensions 22, upon securing of the end portions of the extensions 22 to the inner face of the top 21b of the

cover part, as by glue or the like. The score lines 22a enhance the yieldability of the respective extensions 22. Fig. 6 shows also extensions 25 projecting from the indicated panels of the lateral sides of the body part 20 which serve as means for closing the bottom 20b of the body part 20. The extension 25 cooperates with the extreme right hand panel of the body part 20 for affording overlapping "glue" areas for attaining the hollow configuration of the body part 20.

The embodiment typified by Figs. 7 through 10 corresponds generally to the embodiment of Figs. 1 through 4, and corresponding parts are indicated by like reference characters. The embodiment of Figs. 7 through 10 illustrates the locating of the dispensing opening 21a at a lateral side of the cover part 21 of lesser dimension. The embodiment of Figs. 7 through 10 comprises the further features of locating on the one or more extensions 22 the score line 22c—in lieu of the above referred score line 22a—to effect a "snap" opening and closing action of the cover part 21 relative to the body part 20. Specifically by locating the 22c score line transversely of the direction of length of each extension 22 and at a spacing greater from its end which is secured to the indicated panel of the lateral side of the body part 20 as compared with its spacing from its end which is secured to the top 21b of the cover part 21, an eccentric lever action is produced, thereby causing a "snap" action in the to and fro movements of the cover part relative to the body part.

The embodiment shown in Figs. 7 through 10 features also the embodiment of a stopper element 27 formed either integral with or attached to the end portions of the extensions 22 which are secured to the inner face of the top 21b of the cover part; in the illustrated embodiment 40 such stopper element 27 is shown formed integrally with the extensions 22. Such stopper element 27 serves, when the cover part is in relative closed position with regard to the body part 20, to seal the access opening 20a of the body part 20, for purposes of air-sealing the closure and safe-guarding against loss of flavor or aroma, and precluding "sifting" of contents, and like purposes.

The blanks indicated in Figs. 11 and 12 illustrate one method of forming the body part 20 and cover part 21 of integral construction, inclusive of their respective closing end panels and of the extensions 22; like parts are indicated by like reference characters.

It will be observed with regard to the blank shown in Fig. 11 that the dispensing opening 21a formed in a lateral side of the cover part 21 may be open-ended when the blank 21 is in projected, i. e. plan position. Fig. 11 illustrates also the employment of but two panels 23, projecting from the indicated two panels of oppositely disposed lateral sides of the cover part 21; such arrangement is advantageous in co-action with the thereto "glued" end portion of the extensions 22, see Fig. 12, for dually closing the end 21b of the cover part 21 and forming the stopper means 27, as well as securing the concerned end portions of the extensions 22. The stopper means 27 may comprise suitable material such as cork as additional stopper means, suitably secured to the stated end portions of the extensions 22.

As appears from the aforesaid, the body part and cover part and their respective associated parts 75 may be formed of any suitable resilient stiff sheet

material; sheet material such as cardboard or like paper stock is preferred.

Whereas I have described my invention by reference to specific forms thereof, it will be understood that many changes and modifications may be made without departing from the spirit of the invention.

I claim:

1. In a carton or container, the combination of a hollow body part having adjacent one end an access or discharge opening, the body part being otherwise closed, a hollow cover part arranged for telescopic engagement with said body part adjacent the said one end thereof, and yieldable means comprising relatively stiff sheet material secured at one end to the material of the lateral sides of the body part and at the opposite end to an inner facial area of said cover part for maintaining at all times the stated telescopic engagement of said cover part relative to said body part and for limiting the extent of movement of said cover part in direction away from the major portion of said body part, said yieldable means being additional to said cover part and disposed within the hollow interior thereof, said relatively stiff sheet material having weakened portions to enhance its yieldability, said cover part being provided with a dispensing opening which when the cover part has been moved to or proximate its extended limit position, communicates through the interior of said hollow cover part with the stated access or discharge opening of said hollow body part, the cover part being otherwise closed, the stated dispensing opening of said cover part being moved to its closed position when said cover part and said body part are in maximum telescopic engagement.

2. In a carton or container, the combination of a body part having an open end serving as an access opening, the body part being otherwise closed; a cover part of permanent formation having an open end arranged to receive the open end of the body part to afford telescopic engagement of the cover part relative to the body part, the cover part having a dispensing opening disposed wholly in one of its lateral sides and a closed top and otherwise closed, its dispensing opening being located adjacent its closed top; and yieldable means for positively maintaining at all times telescopic engagement of the cover part relative to the body part and for limiting the extent of the outward movement of the cover part in direction away from the major portion of the body part, said yieldable means having one of its ends positively secured to the body part and its opposite end secured to the inner face of the closed top of the cover part, the effective length of said yieldable means affording when the cover part is in its limited outward position communication of its dispensing opening with the interior of the body part, the dispensing opening of the cover part being closed when the cover part is in retracted position relative to the body part.

3. In a carton or container, the combination of a body part having an open end serving as an access opening, the body part being otherwise closed; a cover part of permanent formation having an open end arranged to receive the open end of the body part to afford telescopic engagement of the cover part relative to the body part, the cover part having a dispensing opening disposed wholly in one of its lateral sides and a closed top and otherwise closed, its dispensing opening being located adjacent its closed top; and yieldable means of sheet material for posi-

tively maintaining at all times telescopic engagement of the cover part relative to the body part and for limiting the extent of the outward movement of the cover part in direction away from the major portion of the body part, said yieldable means having one of its ends positively secured to the body part and its opposite end secured to the inner face of the closed top of the cover part, the effective length of said yieldable means affording when the cover part is in its limited outward position communication of its dispensing opening with the interior of the body part, the dispensing opening of the cover part being closed when the cover part is in retracted position relative to the body part.

4. In a carton or container, the combination of a body part having an open end serving as an access opening, the body part being otherwise closed; a cover part of permanent formation having an open end arranged to receive the open end of the body part to afford telescopic engagement of the cover part relative to the body part, the cover part having a dispensing opening disposed wholly in one of its lateral sides and a closed top and otherwise closed, its dispensing opening being located adjacent its closed top; and yieldable means of relatively stiff sheet material having a transversely extending scoring for positively maintaining at all times telescopic engagement of the cover part relative to the body part and for limiting the extent of the outward movement of the cover part in direction away from the major portion of the body part, said yieldable means having one of its ends positively secured to the body part and its opposite end secured to the inner face of the closed top of the cover part, the effective length of said yieldable means affording when the cover part is in its limited outward position communication of its dispensing opening with the interior of the body part, the dispensing opening of the cover part being closed when the cover part is in retracted position relative to the body part.

5. In a carton or container, the combination of a body part having an open end serving as an access opening, the body part being otherwise closed; a cover part of permanent formation having an open end arranged to receive the open end of the body part to afford telescopic engagement of the cover part relative to the body part, the cover part having a dispensing opening disposed wholly in one of its lateral sides and a closed top and otherwise closed, its dispensing opening being located adjacent its closed top; and yieldable means for positively maintaining at all times telescopic engagement of the cover part relative to the body part and for limiting the extent of the outward movement of the cover part in direction away from the major portion of the body part, said yieldable means comprising two lengths of sheet material, each extending from the edge of the access opening of the body part to the inner face of the closed top of the cover part and provided with a transversely extending scoring disposed substantially equally between the edge of the access opening of the body part and its connection with the cover part, the effective length of said yieldable means affording when the cover part is in its limited outward position communication of its dispensing opening with the interior of the body part, the dispensing opening of the cover part being closed when the cover part is in retracted position relative to the body part.

6. In a carton or container, the combination of

a body part having an open end serving as an access opening, the body part being otherwise closed; a cover part of permanent formation having an open end arranged to receive the open end of the body part to afford telescopic engagement of the cover part relative to the body part, the cover part having a dispensing opening disposed wholly in one of its lateral sides and a closed top and otherwise closed, its dispensing opening being located adjacent its closed top; and yieldable means for positively maintaining at all times telescopic engagement of the cover part relative to the body part and for limiting the extent of the outward movement of the cover part in direction away from the major portion of the body part, said yieldable means comprising two lengths of sheet material, each extending from the edge of the access opening of the body part to the inner face of the closed top of the cover part and provided with a transversely extending scoring disposed substantially unequally between the edge of the access opening of the body part and its connection with the cover part, the effective length of said yieldable means affording when the cover part is in its limited outward position communication of its dispensing opening with the interior of the body part, the dispensing opening of the cover part being closed when the cover part is in retracted position relative to the body part.

7. In a carton or container, the combination of a body part having an open end serving as an access opening, the body part being otherwise closed; a cover part of permanent formation having an open end arranged to receive the open end of the body part to afford telescopic engagement of the cover part relative to the body part, the cover part having a dispensing opening disposed wholly in one of its lateral sides and a closed top and otherwise closed, its dispensing opening being located adjacent its closed top; yieldable means for positively maintaining at all times telescopic engagement of the cover part relative to the body part and for limiting the extent of the outward movement of the cover part in direction away from the major portion of the body part, said yieldable means comprising two lengths of sheet material, each extending from the edge of the access opening of the body part to the inner face of the closed top of the cover part and provided with a transversely extending scoring disposed substantially equally between the edge of the access opening of the body part and its connection with the cover part, the effective length of said yieldable means affording when the cover part is in its limited outward position communication of its dispensing opening with the interior of the body part, the dispensing opening of the cover part being closed when the cover part is in retracted position relative to the body part and a stopper element secured to the inner face of the closed top of the cover part.

8. In a carton or container, the combination of a body part having an open end serving as an access opening, the body part being otherwise closed; a cover part of permanent formation having an open end arranged to receive the open end of the body part to afford telescopic engagement of the cover part relative to the body part, the cover part having a dispensing opening disposed wholly in one of its lateral sides and a closed top and otherwise closed, its dispensing opening being located adjacent its closed top; yieldable means for positively maintaining at all times telescopic engagement of the cover part relative to the body part and

to the body part and for limiting the extent of the outward movement of the cover part in direction away from the major portion of the body part, said yieldable means comprising two lengths of sheet material, each extending from the edge of the access opening of the body part to the inner face of the closed top of the cover part and provided with a transversely extending scoring disposed substantially unequally between the edge of the access opening of the body part and its connection with the cover part, the effective length of said yieldable means affording when the cover part is in its limited outward position communication of its dispensing opening with the interior of the body part, the dispensing opening of the cover part being closed when the cover part is in retracted position relative to the body part and a stopper element secured to the inner face of the closed top of the cover part.

9. A box formed of sheet material and comprising a containing part, a cover part, and articulative linkage interconnecting the said parts, said containing part having lateral panel walls defining a mouth, said articulative linkage comprising a pair of linkage panel members respectively secured to two of those said lateral panel walls which are disposed opposite each other, and each of said linkage panel members comprising panel sections articulatively joined and adapted to fold upon one another substantially bellows-wise, and said cover part being of box formation having lateral panel walls corresponding to the said lateral panel walls of the containing part, and having, further, a closed end and an open end, and being adapted for telescopic movement over the mouth-end of said containing part.

10. A box as recited in claim 9 wherein the articulative linkage is of such length as will allow only limited sliding movement of the cover part upon the mouth end of the containing part, and wherein pouring aperture means is provided in one of those lateral walls of said cover part which is disposed between the said pair of articulative linkage panel members, said pouring aperture means being so located as to be closed by said containing part when said cover part is in retracted telescopic position over said containing part, and as to be open when said cover part is in extended telescopic position over said containing part.

11. A folding box formed of foldable sheet material and comprising a containing part, a cover part, and articulative linkage interconnecting the said parts, the said containing part and the said articulative linkage being formed from a single blank of foldable sheet material cut and scored to provide lateral panel walls defining an open mouth at one end of the containing part and a pair of linkage panel members extending, respectively, from opposite lateral panel walls at said open mouth, each of the linkage panel members of said pair of same being traversed across its width by spaced parallel score lines, providing panel sections articulatively joined and adapted to fold upon one another substantially bellows-wise, and said cover part being formed from a single blank of foldable sheet material cut and scored to provide lateral panel walls, corresponding to the said lateral panel walls of the containing part, and closure flaps and closure supporting flaps for closing one end of said cover part, the said cover part being arranged for telescopic movement over the said mouth-end of the containing part, and the free-end panel sections of

said linkage panel members being secured within said cover part substantially at the closed end thereof.

12. A container comprising a receptacle body part having a dispensing opening; a cover part, the said cover part being adapted to slide in close telescopic fit over the said body part, closing the said dispensing opening thereof; and articulative panel linkage interconnecting the said body part and the said cover part and having length sufficient to allow the said cover part to be slid relative to said body part, thereby opening the said dispensing opening for discharge of contents from said body part, said linkage being secured within said cover part and being adapted to fold upon itself in the closing of said cover part.

13. A container comprising a receptacle body part having a dispensing opening; a cover part, the said cover part being adapted to slide in close telescopic fit over the said body part, clos-

ing the said dispensing opening thereof; and articulative panel linkage interconnecting the said body part and the said cover part and having length sufficient to allow the said cover part to be slid relative to said body part, thereby opening the said dispensing opening for discharge of contents from said body part, said linkage comprising panel sections articulatively joined and adapted to fold upon one another substantially bellows-wise in the closing of said cover part.

14. A container in accordance with claim 12 wherein the cover part is closed at its top end and the articulative panel linkage is secured at the underside of the said closed top end.

15. A container in accordance with claim 13 wherein the cover part is closed at its top end and the articulative panel linkage is secured at the underside of the said closed top end.

R. MURRAY GLOVER.
